Specification for Design.

Patented July 5, 1921.

Application filed October 4, 1920. Serial No. 414,684. Term of patent 7 years.

To all whom it may concern:

Be it known that I, WILLIAM WURTH, a citizen of the United States, residing at Cleveland, in the county of Cuyahoga and State of Ohio, have invented a new, original, and ornamental Design for a Display Device, of which the following is a specification, reference being had to the accompanying drawing, forming part thereof.

The figure is a plan view of a display device, showing my new design.

The device is intended for display in windows for advertising purposes.

I claim:

The ornamental design for a display device, as shown.

WILLIAM WURTH.
